HANDLE FOR AN INSTRUMENT CASE

Lance A. Wilkes and Edward Vescuso, Jr., Canoga Park, Calif., assignors to System Metals, Inc., Canoga Park, Calif.

Filed Sept. 22, 1971, Ser. No. 182,930

Term of patent 14 years

Int. Cl. D8—06

U.S. Cl. D8—154

FIG. 1 is a front perspective view of a handle for an instrument case embodying our new design;

FIG. 2 is a front elevational view thereof;

FIG. 3 is an end elevational view of the end opposite that shown in FIG. 1;

FIG. 4 is a bottom plan view thereof;

FIG. 5 is a rear elevational view thereof; and

FIG. 6 is a front perspective view showing the movable handle member in its raised position.

We claim:

The ornamental design for a handle for an instrument case, as shown.
